By Daniel Breed, Atty.

UNITED STATES PATENT OFFICE.

JAMES BRYANT, OF INDIANAPOLIS, INDIANA.

DENTAL PLATE.

SPECIFICATION forming part of Letters Patent No. 245,607, dated August 16, 1881.

Application filed May 4, 1881. (Model.)

To all whom it may concern:

Be it known that I, JAMES BRYANT, a citizen of the United States, residing at Indianapolis, in the county of Marion and State of Indiana, have invented certain new and useful Improvements in Dental Plates; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention consists of certain new improvements in dental plates, which will be fully understood by the following description and claim.

Figure 1 is a perspective view of improved dental plate for the upper jaw. Fig. 2 is a transverse vertical section of the same. Fig. 3 is a section of the plate for the under jaw. Fig. 4 is a detached section of a tooth and also of a small plate of hard metal riveted thereto.

In applying my invention I make the main central or inner plate, A, of hard metal. This plate extends nearly to the inner edge of the crown of the gums, but not so as to bear on the gums, which are to have a groove of softer metal, as will be soon explained.

Each separate tooth is to be provided with a small plate, G, of hard metal, and this plate is fastened to the tooth by rivets *i*, Fig. 4. In this plate there are small notches *g'*, to facilitate the clench of the soft metal yet to be described.

The hard inner plate, A, is put into a mold formed in the usual way, and the teeth also set in place, with the plate G riveted thereon. Now, the soft molten metal is poured into the mold, thus uniting the hard inner plate and the tooth, and at the same time forming a groove of soft metal for the crown of the gums to bear against, as seen at C, Fig. 1; or, the teeth may be soldered to the soft-metal rim C.

Having thus described my invention, what I claim, and desire to secure by Letters Patent, is—

A dental plate consisting of the hard-metal inner plate, A, and soft-metal rim C, combined with the backing-plates G, having notches *g g'*, and being soldered to both the inner plate, A, and rim C, substantially as set forth.

In testimony whereof I affix my signature in presence of two witnesses.

JAMES BRYANT.
